UNITED STATES PATENT OFFICE

HENRY B. IVEY, OF GOLDSBORO, NORTH CAROLINA

VANITY CASE

Application filed February 13, 1929. Serial No. 339,697.

This invention relates to an improved special article carrier which may be broadly defined as a vanity case and which is made for accommodating and making readily accessible a plurality of different but closely associated devices, whereby to provide a compact and convenient assemblage for use particularly by the feminine sex.

The principal aim is to provide a novel contribution to this art which is economical in use and construction, unusually handy, exceptionally efficient in performance, and capable of fulfilling the requirements of a product of this class, in a successful manner.

15 In the drawings:

Figure 1 is a view in section through the complete device, showing the relative association of parts.

Figure 2 is a top plan view thereof.

20 Figure 3 is a bottom plan view.

Figure 4 is a horizontal sectional view taken approximately on the line 4—4 of Figure 1.

25 Figure 5 is a horizontal section taken on the line 5—5 of Figure 1.

Figure 6 is a horizontal sectional view through the body portion of the casing.

Figure 7 is a top plan view of the swingable door of the casing.

30 Figure 8 is a perspective view of a special detail.

In carrying out the invention I provide a novel cylindrical casing which includes the body portion 9 seen better in Figure 6. This 35 embodies a disc like bottom 10 at one end and a shallow special article receptacle 11 at the opposite end.

Obviously this receptacle is intended to accommodate individual cosmetic articles.

40 In connection with this invention, I invite attention to the part 12 which designates a cover hingedly mounted as at 13 and provided on its interior with a mirror 14. The

reference character 15, in Figure 6, designates an open ended cylindrical compartment which is adapted to contain two distinguishable parts.

45 The reference character 16 designates a cylindrical fluid container which has its snug friction fit and which is adapted to contain a well known ignitor fluid. This

50 container is provided at its bottom with an inflammable wick 17. Arranged in the upper compartment is a cylindrical battery 18 whose upper contact is positioned for electrical engagement with the contact of a miniature illuminating bulb 19. This bulb is arranged in the receptacle 11. The device 20 shown in Figure 8, is associated with this compartment and also with the parts 16 and 18. This device comprises a partition disc 21 arranged 55 between the adjacent ends of the parts 16 and 18 and provided with a central contact button 22 which rests against the bottom of the battery.

55 There is also a current conducting arm 23 which extends alongside of the battery up through an opening in the bottom of the receptacle 11. On the upper end is a knob like externally arranged contact 24, which, when the lid 12 is swung open completes the 60 circuit to light the bulb 19. There is also an inwardly extending retaining finger 25, normally spaced above the bottom of the receptacle. This serves to maintain the device 20 in place, when the cylindrical compartment 15 is empty.

65 A substantially semi-circular cover 26 is hinged as at 27 (see Figure 5) to the casing. This cover is provided at its bottom with a retaining finger 28, cooperable with the headed stud 29 for limiting the opening of the cover or door 26. However, by disengaging this part 28 from the pin 29, the cover can be completely opened as shown in Figure 3. Swingably mounted within the casing and concealed by the door 26 is a cigarette carrier 30. This comprises the segmental body whose inner portion conforms to and surrounds the cylinder 16 and whose outer vertical face is formed with a plurality of channels for cigarettes 31. As shown in Figure 1, the receptacles comprise vertical grooves having sockets 32 at their lower ends in which the cigarettes are placed. In addition, a spring retaining band 33 is provided 85 for holding the cigarettes in place.

90 Obviously, then, when the door 26 is swung open, the cigarette carrier 30 is readily accessible for convenient removal and use of the cigarettes.

Cooperating with the aforesaid miniature liquid tank 16 and wick 17 is the lighting means for the wick represented in Figure 3, this being mounted on the bottom of the casing. It comprises an encased lever 34 provided with the flint positioned in the flint holder 35. The parts are so arranged as to produce a spark as represented in Figure 3 for igniting the wick 17.

From the foregoing description it will be seen that the gist of the invention is in providing a single device including a plurality of distinguishable features. For instance, at the top of the casing is a special article container for cosmetics, a hinged lid with a mirror, and a supplemental illuminating bulb or light for illuminating the face of the mirror to render the mirror usable at night time. Then there is a conveniently located and readily removable battery. Incidentally it should be stated that the disc 21 is detached from the arm 23 and the arm rests in current conducting contact with the periphery thereof, the disc being positioned between the tank 16 and the battery 18, whereby to facilitate removal and renewal of the parts. It is further to be stated that the light 19 is illuminated when the cover is swung open and brought into electrical engagement with the contact knob 24.

A further feature to be noted is the cigarette and cigar lighter conveniently positioned on the bottom of the receptacle as well as the swingably mounted closing door and the swingably mounted cigarette carrier on the interior of the casing. All of these parts are so associated as to provide for compactness and convenience of arrangement and ready accessibility.

A careful consideration of the drawings in conjunction with the specification will enable the reader to obtain a clear understanding of the features and advantages of the invention. Therefore a more lengthy description is regarded as unnecessary.

Minor changes in the shape, size and rearrangement of details coming within the field of invention claimed may be resorted to, in actual practice, if desired.

I claim:

A special article carrier of the character described comprising a cylindrical casing having an open side, said casing closed at its opposite end, a cylinder extending longitudinally through the casing adjacent one side thereof adapted to contain a storage battery, a hinged closure for the opening mounted on the casing, a cigarette carrier mounted in the casing and comprising a body portion which is co-extensive with the interior of the casing and provided with a longitudinally extending recess in one side for the reception of the cylinder and having parallel vertical channels in its periphery at a point substantially diametrically opposite from the recess and

communicating with the opening in the side of the casing, said body portion being further provided, at its lower side, with a series of sockets communicating with the adjacent ends of the channels for the reception of the ends of the cigarettes and an arcuate resilient retaining arm mounted on the body portion and extending transversely across the channels intermediate their ends for retaining the cigarettes therein.

In testimony whereof I affix my signature.

H. B. IVEY.
